UNITED STATES PATENT OFFICE.

FREDERIC W. COX AND CHARLES F. COX, OF BRIDGETON, NEW JERSEY, ASSIGNEES
TO THE COX AND SONS COMPANY, OF BRIDGETON, NEW JERSEY, A CORPORATION
OF NEW JERSEY.

PIPE-THREADING DIE.

Application filed August 9, 1923. Serial No. 656,486.

This invention relates to improvements in pipe threading dies of the type forming the subject of the copending application of Warren E. Glaspey and Frederic W. Cox, Serial Number 598,575, now Patent No. 1,569,740, issued January 12, 1926, and relates more particularly to improvements in the construction of the chaser holders and in the methods for adjusting and securing the chasers in the holders.

One object of the invention is to provide means for insuring retention of the chaser in the holder without slippage, and another object of the invention is to provide means for obtaining a uniform position of the chasers in their respective holders.

The means by which we attain the aforesaid objects are clearly illustrated in the attached drawings, in which:

20 Figure 1, is a face view of a holder with the chaser in place;

Fig. 2, is a side view of the said holder and chaser;

25 Fig. 3, is a detached perspective view of the chaser; and

Fig. 4, is a detached perspective view of the chaser clamping element of the holder.

With reference to the drawings, 1 indicates the holder which, as fully described in 30 the copending application of Warren E. Glaspey and Frederic W. Cox, is adapted for insertion in a die and which for the purpose of the present invention may be considered as comprising a main body portion 2 having 35 a beveled recess 3 for the reception of the correspondingly beveled end of a chaser 4, and comprising further a clamping element 5 having an overturned or flanged edge 6 adapted to fit within a correspondingly 40 shaped recess 7 in the chaser 4, said clamping element in conjunction with suitable retaining bolts 8, 8, being adapted to hold the said chaser firmly on its seat in the holder. Means is also provided including a lever 45

9 pivotally secured at 11 to the said holder and an eccentric adjusting bolt 12 operatively connected with the lever for adjusting the chaser 4 in the holder, the manner in which the said lever 9 is connected with the 50 chaser and the method by means of which the adjustment is made being fully set forth in the aforesaid copending application of Warren E. Glaspey and Frederic W. Cox, but by reason of the fact that this feature 55 of the construction has no direct bearing

upon the present invention, the details of this device may be passed over.

As best illustrated in Fig. 2, the holder and the clamping element 5 have inclined abutting surfaces 13 and 14, and by reason 60 of the fact that in operation these surfaces normally meet only at the lower edge of the clamp 5, tightening of the bolts 8, 8, has a tendency not only to force the chaser down into the recess 3 but also to shift the clamping element rearwardly in such manner as to pull the chaser tightly against the holder. All this has been fully set forth and claimed in the copending application of Warren E. Glaspey and Frederic W. Cox, Serial Num- 70 ber 598,575.

It has been found, however, that under some circumstances there has been difficulty in retaining the chaser 4 in precise adjustment in the holder, and difficulty has also 75 been experienced in adjusting the chaser accurately in the holder. We have discovered that by knurling or suitably scoring engaging surfaces of the clamping element 5 and the chaser 4, the difficulty of adjustment and 80 of retaining the adjustment is entirely eliminated. Thus, as clearly illustrated in Figs. 3 and 4, we may knurl or otherwise roughen the edge 15 of the chaser 4 which fits in back of the edge 6 of the clamping element 5, or 85 the contacting surface 16 of the clamp 5, or both the surfaces 15 and 16, and as illustrated in the drawings the knurlings preferably extend transversely of said surfaces. Such knurling or roughening of these parts 90 entirely eliminates any tendency of the chaser to slip from its adjusted position when the clamp is tightened.

We claim:

1. In a die head, the combination of a 95 chaser holder, a clamp adapted to engage a chaser in the holder, and means for exerting pressure on the clamp, the said holder and the said clamp having cooperating opposed gripping surfaces for holding the chaser 100 when pressure is applied to the clamp and along which the chaser is linearly adjustable when the clamp is released, and one of the said surfaces being grooved or knurled in a direction transverse to the direction of the 105 aforesaid linear adjustment.

2. In a die head, the combination of a chaser holder, a clamp adapted to engage a chaser in the holder, and means for exerting pressure on the clamp, the said holder 110

- and the said clamp having cooperating opposed gripping surfaces for holding the chaser when pressure is applied to the clamp and along which the chaser is linearly adjustable when the clamp is released, the said surface on the holder being smooth and the said surface on the clamp being grooved or knurled in a direction transverse to the direction of the aforesaid linear adjustment.
3. In a die head, the combination of a chaser, a chaser holder having a seat for the chaser, a clamp mounted on the holder and adapted to engage the chaser, means for exerting pressure on the clamp, the said holder and the said clamp having cooperating opposed gripping surfaces for holding the chaser when pressure is applied to the clamp and along which the chaser is linearly adjustable when the clamp is released, and the engaging surfaces of the chaser and the clamp being grooved or knurled in a direction transverse to the direction of the aforesaid linear adjustment.
4. In a die head, the combination of a chaser having longitudinal thread grooves in one face thereof and having a longitudinal beveled surface and an opposed longitudinal gripping surface, a chaser holder having a beveled seat for engaging the beveled surface of the chaser, and a clamp having a gripping surface adapted to engage the gripping surface of the chaser, one of the said gripping surfaces being transversely grooved or knurled so that the chaser may be more firmly held by the clamp against longitudinal movement.
5. In a die head, the combination of a chaser having longitudinal thread grooves in one face thereof and having a longitudinal beveled surface and an opposed longitudinal gripping surface, the said chaser also having a longitudinal groove adjacent the said gripping surface, a chaser holder having a beveled seat for engaging the beveled surface of the chaser, and a clamp having a gripping surface adapted to engage the gripping surface of the chaser and also having a flange adapted to enter the groove in the chaser, the said gripping surfaces of the clamp and chaser being transversely grooved or knurled so that the chaser may be more firmly held by the clamp against longitudinal movement.
6. For a die head, a chaser having longitudinal thread grooves in one face thereof and having a longitudinal beveled surface and an opposed longitudinal gripping surface, the said gripping surface being transversely grooved or knurled so that the chaser may be firmly held by a clamp against longitudinal movement.
7. For a die head, a chaser having longitudinal thread grooves in one face thereof, and having a longitudinal beveled surface and an opposed longitudinal gripping surface and also having a longitudinal groove adjacent the gripping surface, the said gripping surface being transversely grooved or knurled so that the chaser may be firmly held by a clamp against longitudinal movement.
